[57] CLAIM

The ornamental design of a spraying device, as shown and described.

DESCRIPTION

FIG. 1 is a right side elevational view of a spray wand device showing my new design;

FIG. 2 is a top plan view thereof;

FIG. 3 is a bottom plan view thereof;

FIG. 4 is a left side elevational view thereof;

FIG. 5 is a front elevational view thereof; and

FIG. 6 is a rear elevational view thereof;

FIG. 7 is a right side elevational view of a modified form of the spray wand shown in FIG. 1, the left side being the same as the right side shown;

FIG. 8 is a right side elevational view of a second modified form of the spray wand shown in FIG. 1, the left side being the same as the right side shown;

FIG. 9 is a top plan view of FIG. 8;

FIG. 10 is a front elevational view of FIG. 8;

FIG. 11 is a right side elevational view of a third modified form of the spray wand shown in FIG. 1, the left side being a mirror image of the right side shown;

FIG. 12 is a top plan view of FIG. 11; and

FIG. 13 is a bottom plan view of FIG. 11.
